Cortland, Ohio

Application October 16, 1957, Serial No. 48,124

Term of patent 7 years

(Cl. D26—5)

FIG. 1

FIG. 2

FIG. 3

Figure 1 is a perspective view of a combined floodlight bracket and outlet box, showing our new design;

Figure 2 is an enlarged perspective view showing the back thereof; and

Figure 3 is a horizontal section on line 3—3 of Figure 2.

The fragmentary broken line showing of flood lamps and a building corner are for illustrative purposes only.

We claim:

The ornamental design for a combined floodlight bracket and outlet box, as shown and described.
